UNITED STATES PATENT OFFICE.

FRED SPANGLER, OF MIDWAY, WISCONSIN.

GRINDING DEVICE.

Application filed September 25, 1923. Serial No. 664,754.

To all whom it may concern:

Be it known that I, FRED SPANGLER, citizen of the United States of America, residing at Midway, in the county of La Crosse and State of Wisconsin, have invented certain new and useful Improvements in Grinding Devices, of which the following is a specification.

The present invention relates to a grinding device particularly adapted to be mounted upon a silo-filler or other light machinery for the purpose of sharpening the cutting knives thereof.

The principal object of the invention is to provide a grinding device which is simple and efficient in structure, revolvable in operation, comparatively inexpensive to manufacture, durable, easy of manipulation, and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing:

Figure 1 is a front elevation of the device embodying my invention,

Figure 2 is a top plan view thereof,

Figure 3 is a side elevation thereof,

Figure 4 is a vertical section therethrough, and

Figure 5 is a detail perspective view of the operating arm for the grinding wheel.

Referring to the drawing in detail, it will be seen that the device includes a frame possessed of two inverted U-shaped sides which are connected at their intermediate or proper portion by a rod 6. These inverted U-shaped sides are securely fastened to the beams 7 which are provided with suitable brackets so that the device may be readily attached to a silo-filler or some other suitable or desired machinery. A journal box 9 is associated with each of the sides 5. Each journal box includes a block 10 having grooves in its sides for receiving the legs of the inverted U-shaped side with which it is associated. A sleeve extends from the block 9 as indicated at 11 and an extension 12 is provided thereon from which extends upwardly a stem 13. This stem 13 projects through an aperture provided in a bracket 14 mounted on one leg

of the side 5 adjacent its intermediate or top portion. A thumb screw 15 is threadedly engaged with the stem above the bracket 14 and thus the journal box may be raised or lowered as desired. An extensible coil spring 16 is disposed about the stem between the bracket 14 and the extension 12 normally holding the journal box at its down-most position so that the nut 15 is resting on the bracket 14. This spring also tensions the grinding device against the blades which it is sharpening as will be more evident as the description progresses.

A shaft 17 is journaled in the boxes 9 and terminates at one end in a pulley 18. The portion of the shaft 17 between the sides 5 is provided with a longitudinally extending key 18. A grinding element is mounted on this shaft 17 and includes a sleeve or tubular member 19 having a grinding wheel 20 thereon preferably formed of emery. The sleeve or tubular member 19 will rotate with the shaft 17 because of the key 18, and this sleeve or tubular member may be moved longitudinally on the shaft. The wheel 20 is suitably fixed to the tubular member 19 so as to rotate therewith. A rod 22 extends between the beams 7 and sides 5 but forwardly of the latter. An arm 23 is provided with a sleeve 24 intermediate its ends for receiving this rod 22 whereby the arm may be moved across the device. This arm terminates in a forked end as is shown to advantage in Figure 4 and said forked end engages an annular groove 25 provided in the sleeve or tubular member 19 and thus this tubular member and its grinding wheel may be readily moved across the device or longitudinally of the shaft 17 as is desired during the operation of the grinding wheel.

A belt 27 is trained over the pulley 18 and also over another power wheel 28 which may be driven from any part of the silo-filler or other machinery upon which the device is being used. An idler 29 is mounted on an arm 30 and a spring 31 holds it in engagement with the belt 27. It is thought that the construction and operation of the invention should now be understood without a more specific description thereof. It is, however, desired to point out that numerous changes in the details of construction, materials, and in the combination and arrangement of parts may be resorted to without departing from the spirit of the invention or sacrificing any of its advantages.

Having thus described my invention, what I claim as new is:—

5. 1. In a grinding device of the class described, a frame including a pair of inverted U-shaped sides, journals slidable in the sides, a shaft in the journals, means for rotating the shaft, and a grinding wheel rotatable by the shaft and slidable longitudinally thereof.
10. 2. In a grinding device of the class described, a frame, a shaft in the frame, a sleeve rotatable with the shaft and slidable thereon and provided with an annular groove, a grinding wheel fixed to the sleeve, a rod mounted in the frame parallel with the shaft, and an arm including a sleeve disposed intermediately thereof receivable on the rod and a bifurcated end receivable in the annular groove of the sleeve whereby 20 the grinding wheel may be moved longitudinally of the shaft all in the manner and for the purpose specified.
25. 3. In a grinding device of the class described, a frame, journal boxes slidable in the frame, a shaft in the journal boxes, a grinding wheel on the shaft, brackets on the frame, stems extending from the journals through the brackets, nuts threaded upon the stems above the brackets and springs disposed about the stems between the journals and the brackets for tensioning purposes all in the manner and for the purpose specified.
30. 4. A grinding device of the class described, a frame including a pair of inverted U-shaped sides, each side including a pair of upright rails and an intermediate curved portion, journals provided with side grooves for receiving the upright rails on the U-shaped sides of the frame and slidably mounted therein, a shaft in the journals, means for rotating the shaft, and a grinder wheel rotatable on the shaft and slidably longitudinally thereof.
45. 5. A grinding device of the class de-

scribed, a frame including a pair of inverted U-shaped sides, each side including a pair of upright rails and an intermediate curved portion, journals provided with side grooves for receiving the upright rails of the U-shaped sides and slidably mounted therebetween, a shaft in said journals, a grinding wheel on the shaft, means for rotating the shaft, and means associated with the slidably mounted journals for holding the grinding wheel against an object.

6. In a grinding device of the class described, a frame including a pair of inverted U-shaped sides, each side including a pair of spaced uprights and an intermediate connecting portion at their top ends, journals provided with grooves in their sides for receiving the uprights so as to be slidably mounted in the sides, a shaft mounted in the wheels, a grinding wheel on the shaft, brackets extending from the uprights, stems piercing the brackets and extending therebelow and attached to the journals, and nuts threaded on the upper end of the stems.

7. In a grinding device, a frame including a pair of inverted U-shaped sides, each side including a pair of uprights, and an intermediate connecting portion at their top ends, journals provided with grooves in their sides for receiving the uprights so as to be slidably mounted in the sides, a shaft mounted in the journals, a grinding wheel on the shaft, brackets extending from the uprights, stems piercing the brackets and connected to the journals, threads on the stems above the brackets, springs disposed about the stems between the journals and the brackets for normally holding the journals in their downmost position and nuts on the threads of the stem above the brackets.

In testimony whereof I affix my signature.

FRED SPANGLER.
